HOT WATER DRAIN DEVICE

Oscar Brooks, Arkadelphia, Ark.

Application July 11, 1941, Serial No. 402,005

1 Claim. (Cl. 137—79)

My invention relates to improvements in devices for draining the hot water systems of dwellings and the principal object in view is to provide simply constructed, easily installed means whereby both the hot and cold water pipes of such systems are drained dry throughout when the water is cut off from the water service line.

To the accomplishment of the above, and subordinate objects presently appearing, a preferred embodiment of my invention has been illustrated in the accompanying drawings, set forth in detail in the succeeding description, and defined in the claim appended hereto.

In said drawings—

Figure 1 is a schematic view partly in vertical section and partly in side elevation of the preferred embodiment of my invention.

Figure 2 is a view in horizontal section taken on the line 2—2 of Figure 1 and drawn to an enlarged scale.

Figure 3 is a view in side elevation of the drain fitting drawn to an enlarged scale.

Figure 4 is a view in end elevation of said fitting, and

Figure 5 is a view in longitudinal section taken on the line 5—5 of Figure 3.

Reference being had to the drawings by numerals, my improvement has been illustrated therein as embodied in a water installation system, in which 1 is the service line extending into the cellar 2 and terminating in a water supply cut-off valve 3 having the usual bleed drain opening 4. The cold water pipe 5 branches from the discharge end of the valve 3 and extends horizontally beneath the floor F. A cold water feed branch 6 extends from the pipe 5 into the top of the hot water boiler 7 and down into the bottom of the latter. A second cold water branch 8 extends from said pipe 5 to the sink fixture 9. A third cold water branch 10 extends from the pipe 5 upwardly through a wall W for the bathroom supply. The numeral 11 designates the hot water pipe extending horizontally with the hot water branch 12 leading from the top of the boiler 7 thereto, a second hot water branch 13 extending from therefrom to the sink fixture 9 and a third hot water branch 14 extending upwardly through said wall for the bathroom supply.

Intermediate the described hot and cold water branches and the cut-off valve 3, the hot water pipe 11 is connected at one end to the cold water pipe 5 by a preferably horizontally extending, tubular, valved drain fitting 15 having its opposite ends externally threaded, as at 16, 17, said ends being turned into suitable couplings 18, 19

5 respectively. The fitting 15 is provided in the end thereof coupled with the cold water pipe 5 with a cylindrical valve chamber 20 terminating at its inner end in a semi-circular valve seat 21, said fitting having an axial counterbore 22 therein extending from said seat 21 to the other end of the fitting. A ball valve 23 is confined in the chamber 20 by a diametrical pin 24 extending 10 through the chambered end of the fitting, said ball as best shown in Figure 5 being smaller in diameter than the diameter of the chamber 20. As will be manifest, the ball valve 23 is adapted to fit the seat 21 and to close the bore 22 by movement thereon inwardly of the fitting 15. As will also be manifest, the fitting 15 is arranged in the described system so that as long as the water is turned on and there is pressure in the cold water line 3, the ball valve 23 will be held seated by such 15 pressure to close the fitting 15.

Referring now to the operation, when the described cut-off valve 3 is closed, the cold water pipe 11 together with its branches 6, 8, and 10 will drain through the bleed opening 4. Pressure 20 on the ball valve 23 being relieved said ball valve will gravitate away from the seat 21 to open the fitting 15 so that the hot water pipe 11 together with its branches 12, 13 and 14 may drain into the cold water pipe 5 and out of the bleed opening 4.

In the usual water system there are two drain cocks, one for the hot water side, and one for the cold water side. This results in confusion and the hot water drain cock being frequently 25 opened while the cold water is on, with the result that a stream of water is running out of the system unknown to the tenant of a house until he subsequently discovers the situation. My invention obviates any such contingency arising 30 since only one drain cock is required in the system. This also reduces the cost of installation and servicing as will be apparent.

The foregoing will, it is believed, suffice to impart a clear understanding of my invention 35 without further explanation.

Manifestly the invention, as described, is susceptible of modification without departing from the inventive concept, and right is herein reserved to such modifications as fall within the 40 scope of the subjoined claim.

What I claim is:

In a water installation system, a service line 45 for water under pressure, a cold water line, a combination cut-off and drain valve connecting said line to said pipe constructed and arranged

in one position to admit water under pressure to said line and in another position to drain said line, a hot water line communicating with said cold water line through conventional water heating means and including portions at levels incapable of being drained through the cold water line, means including a pipe line connecting said hot water line to the cold water line arranged to

5 effect drainage of the said portions of the hot water line, a check valve in said pipe line constructed and arranged to close said pipe line to flow of cold water from the cold water line to the hot water line when the cold water line is under pressure and to open when the pressure is relieved.

OSCAR BROOKS.
